UNITED STATES PATENT OFFICE.

CHARLES LUNDY, OF RENO, NEVADA.

VALVE STRUCTURE.

1,170,918.

Specification of Letters Patent. Patented Feb. 8, 1916.

Application filed June 3, 1914. Serial No. 842,622.

To all whom it may concern:

Be it known that I, CHARLES LUNDY, a citizen of the United States, residing at Reno, in the county of Washoe and State of Nevada, have invented certain new and useful Improvements in Valve Structures, of which the following is a specification.

The present invention relates to improvements in internal combustion engines and relates more particularly to that type of engine wherein the puppet valve is dispensed with, and has for its principal objects to provide a construction wherein there is employed a single valve which is adapted for admitting the explosive mixture to the cylinder for providing a communication between the igniting means and the interior of the cylinder, and for controlling the escape of the exploded gases from the cylinder; one by the employment of which the leakage of compression from the cylinder is prevented, and one which is simple in construction, is composed of but few parts, and is thoroughly efficient for the purpose intended.

With the above mentioned and other objects in view, the invention consists in the novel construction and combination of parts hereinafter described, illustrated in the accompanying drawings, and pointed out in the claims hereto appended; it being understood that various changes in the form, proportion, size and minor details of construction, within the scope of the appended claims may be resorted to without departing from the spirit or sacrificing any of the advantages of the invention.

To more fully comprehend the invention, reference should be had to the accompanying sheets of drawings, wherein—

Figure 1 is a view in vertical section of my gas engine. Fig. 2 is a transverse sectional view taken on line 2—2 of Fig. 1. Fig. 3 is a view in plan of the rings positioned between the valve and valve casing.

Referring more particularly to the several views of the drawing, wherein like characters of reference designate corresponding parts throughout the several views—1 is the crank case which also forms the bed, and 2 is the cylinder. I have here shown but one cylinder though it will be readily understood that the engine may comprise a plurality of cylinders. The cylinder is revolvably locked to the bed by any suitable connection which will enable it to

resist end-thrust due to explosion and will adapt it for rotation about its axis. The connection which I deem the best and which I have illustrated is constructed as follows: 60 The top of the crank case or bed 1 is formed or is provided with an annular flange or seat 3. In the base of the seat is an annular bearing ring 4 in the upper surface of which is a ball-race. The lower end of the cylinder is fitted in the seat 3 and said end is provided with or has secured to it a bearing collar 5, which is here shown as screwed upon it, said collar having in its lower face a ball-race. Balls 6 lie in the opposing raceways of the ring 4 and collar 5 and form the support for the cylinder. In the upper face of the bearing collar 5 is a ball-race. Screwed into the top of the seat 3 is an annular nut 7 in the lower face of which is a ball-race. Balls 8 lie in the opposing races of the collar 5 and the nut 7 and form the upper or lock connection for the cylinder. Thus between the two sets of ball bearings the cylinder is locked against end 70 thrust and is adapted for free rotation on its axis. Suitable means driven by the engine are provided to effect this rotation. These in their best form are here shown as follows: 9 is the piston mounted in the 85 cylinder, and 10 is its connecting rod. This rod passes down into the bed or crank case 1 and is connected with the crank 11 of the crank shaft 12, which is mounted in bearings 13 in the bed and carries the fly wheel 90 14. 15 is a countershaft mounted in suitable bearings 16 and 17, as shown in Fig. 2, and said shaft carries a worm 18 meshing with a worm gear 19 which in the present case is shown as formed integral with the 95 bearing collar 5, on the cylinder 2. The worm 18 is best inclosed in a suitable housing 20 formed with the seat 3, as seen in Fig. 2. Upon the end of the countershaft is a gear 21 housed in an extension 22 of the 100 crank case or bed 1. With this gear 21 engages a gear 23 on the crank shaft 12. It will be readily understood by those skilled in the art that these power transmitting connections are properly proportioned to 105 effect the timely rotation of the cylinder as will presently appear.

In order to make a proper gas tight anti-friction bearing between the rotatable cylinder and its non-rotatable reciprocative piston, I employ the following construction: 110 The piston 9 is provided with an outer shell

24 fitted with packing rings 25 between its outer surface and the cylinder wall. The top of the shell 24 is closed and its open bottom has screwed into it a bearing ring 26. Ball bearings 27 lie between the upper end of the piston and the closed top of the shell, and other ball bearings 28 are disposed between the base of the piston and the bearing ring 26 of the shell. It will now be seen that the shell 24 reciprocates with the piston and rotates with the cylinder and that the connection is gas tight and anti-frictional.

An annular valve casing 29 is stationarily mounted above the cylinder, on the stay rods 30 which extend through ears projected from the outer surface of said casing, and said casing is provided respectively with the intake port 31, the exhaust port 32, and the aperture 33, in which is mounted a suitable spark plug 34. The upper portion of the cylinder is formed with a central arranged opening in which is threaded to rotate with the cylinder a suitable valve 35 formed with an L-shaped port 36 therein which opens at one end in the annular side wall 37 of the valve which is in frictional contact with the inner surface of the casing 29, and at its opposite end opens into the upper central portion of the cylinder.

The valve is formed on its interior with the air space 39 for the circulation of air around the port 36, the air contacting with the heat radiating vanes 40 and 41, one connecting the top wall of the port 36 with the annular side wall 37 and the other formed on the inner surface of the side wall. On the rotation of the cylinder in its cycle, the valve is timely rotated to present the port 36 first to the intake port 31, then to the ignition opening 33 and lastly to the exhaust port 32.

To maintain a tight joint between the inner surface of the wall of the valve casing 45 and the outer surface of the wall of the valve, the valve is formed with a plurality of annular channels in its surface, one adjacent each upper and lower edge, and one at its central portion, and in the upper and lower channels are mounted the interlocking packing rings 42. Mounted in the central channel are the concentrically arranged split packing rings 43 and 44, which are provided with aligned openings 45, which register with one end of the L-shaped port 36. The rings taper from their center toward their split ends, and the split ends thereof are preferably arranged diametrically opposite each other, as in Fig. 3 of the drawings, to prevent a leakage between the meeting ends thereof. To insure a registering of the openings 45 with the upper end of

the L-shaped port 36, the wall of the valve carries an outwardly projecting pin 37 which extends through the body of the rings and locks the same to rotate with the valve.

It will be apparent that by providing the rings between the valve and casing, that the compression or products of combustion will be prevented from escaping from the cylinder except at such times as the port of the valve is in register with certain ports in the valve casing.

I claim:

1. In a valve structure for gas engines, the combination with a cylinder of a hollow rotatably mounted valve associated therewith and formed with a channel adapted for communication with the interior of the cylinder, a series of cooling vanes arranged within the hollow interior of the valve, a valve casing surrounding said valve and provided with a plurality of ports, means for operating said valve to present the port therein successively to the ports in said casing to provide a communication between the interior of the said cylinder and the ports, a packing ring carried by the rotating valve and interposed between the valve and the valve casing and rotatable with the valve, the packing ring being rigidly attached to the valve and provided with an opening therethrough intermediate its edges for registering with the channel in the valve.

2. In a valve structure for gas engines, the combination with a rotary cylinder formed with a port in its head, with a hollow rotary valve carried by the cylinder and having a substantially L-shaped channel therein communicating at its lower end with the port in said cylinder, a series of spaced outstanding cooling vanes arranged within the hollow interior portion of the valve, a valve casing surrounding said valve and provided with a plurality of ports, means for rotating the cylinder to successively present the upper end of said channel to the said ports in the valve casing, a packing ring of substantially greater width than the valve interposed between the valve and valve casing and secured thereto by means of a fastening lug, said packing ring being provided with a port intermediate its edges registering with the channel in the valve; and a relatively narrow packing ring seated within the valve on each side of the said ported packing ring.

In testimony whereof I have signed my name to this specification, in the presence of two subscribing witnesses.

CHARLES LUNDY.
